LONGITUDINAL DELIVERED ROTARY IMPACT TOOL

John Charles Sharman, Birmingham, England,
assignor to Garringtons Limited, a British
company

Application December 6, 1950, Serial No. 199,403
In Great Britain December 16, 1949

3 Claims. (Cl. 81—52.35)

1

This invention relates to screwdrivers, wrenches and like hand operated tools for operating on screws, bolts, nuts and like threaded members and is intended primarily for application to such hand operated tools for use in loosening or removing such threaded members under circumstances in which they are unduly tight in position so that they cannot be loosened or removed by ordinary screwdrivers, wrenches and the like of conventional form which merely exert a steady torque on the threaded member with which they are engaged. One particular application of the invention is to the removing of screws, bolts, nuts or like threaded members which have been in position for a considerable period and have corroded in situ so that their removal by tools of conventional form as aforesaid may be impossible. A further application of the invention is to the securing of screws, bolts, nuts, or like threaded members in a particularly tight manner so that these are retained more securely than is the case where tools of conventional form are used which exert merely a steady tightening torque on the threaded member.

One of the objects of the present invention is the provision of a new or improved tool for the purposes above described which is of a particularly compact form.

Another object of the invention is the provision of a tool for the purposes above described which can readily be operated in the conventional way when necessary.

Other objects will be apparent from the following description, claims and from the accompanying drawings in which:

Figure 1 is a side elevation of one form of screwdriver embodying the present invention.

Figure 2 is a cross sectional side elevation of the screwdriver depicted in Figure 1.

Figure 3 is a side elevation of a further form of screwdriver embodying the present invention.

Figure 4 is an inverted plan view of the construction depicted in Figure 3 showing the handle member in the inoperative position.

Referring firstly to Figures 1 and 2 of the drawings the tool which in the arrangement illustrated is a screwdriver comprises an operating element 10 including a screwdriver bit 11 adapted operably to engage with the threaded member to be loosened, removed or tightened, namely a screw of conventional form, the tool further comprising a striking head element 12, the end 13 of which is adapted to be hit by a hammer or other percussion tool.

The striking head element 12 has rigidly 55

associated therewith a cylindrical part 14 formed with a pair of holes 15 extending diametrically therethrough and intersecting with one another on the longitudinal axis of the tool, that is to say, on the axis of the screw to be turned.

10 Integrally connected to the cylindrical part 13 is a tubular portion 16 formed in opposite sides thereof with a pair of elongated openings in the form of slots 17, the two slots being oppositely inclined to the longitudinal axis of the tool and working within the two slots is a pin 18 which extends transversely of the length of the tool, the pin having its opposite ends disposed each in one of the slots and extending medially through 15 a diametrical hole in the cylindrical part 19 of the operating element 10.

The tubular portion 16 is axially slidable over the exterior of the cylindrical part 19 and by reason of the inclined disposition of the slots 17 20 the effect of sliding the tubular portion 16 relative to the operating element 10 in this way is to impart torque to the operating element tending to rotate it about the longitudinal axis of the tool.

25 The inner end of the cylindrical part 19 which is within the tubular portion 16 is recessed at 20 to receive one end of a compression spring 21, the other end of which engages with a spigot 22 provided on a pin 23 axially slidable within a recess 24 provided at the end of the tubular portion 16 which is nearest to the striking head 13, this pin carrying a projection 25, the outer end 30 26 of which is adapted to engage with a handle member in the form of a tommy bar 27 when this is inserted through either pair of the holes 15 so as frictionally to locate the tommy bar in position and restrain it from moving laterally in 35 relation to the tool.

The spring 21 in addition to serving to locate the tommy bar in position in this way serves also 40 as a cushion between the operating element 10 and the striking head element 12 when the latter is hit with a percussion tool and serves further to restore the parts to their initial position.

45 In operation the tommy bar 27 is inserted through one of the two pairs of holes 15, the screwdriver bit 11 is engaged with the screw to be loosened, removed or tightened. The tommy bar 27 is now grasped firmly by one hand of the user so as to prevent the striking head element 12 50 from turning about the longitudinal axis of the tool, the end 13 thereof is hit sharply by a hammer or other percussion tool wielded by the other hand of the user, thus causing the striking head element to move suddenly axially in relation to

the operating element 10 and as the striking head element is being held against rotation torque is suddenly applied through the inclined slots 17 to the pin 18 and thence to the screwdriver bit 11 turning this sharply so as to apply a sudden torque to the screw and thus loosen, remove or tighten this as desired.

The tool may be used in the manner described both during the actual initial loosening of a tight screw or in the final tightening of the same, while during the remaining part of the operation of removing the screw or during the initial screwing of the screw into position the tool may be used as a screwdriver in the usual way by withdrawing the tommy bar 27 from the transverse hole 15 of the operative position shown so that it is detached entirely from the tool which can then readily be grasped in the palm of the user's hand or between the fingers and turned without the tommy bar interfering in any way with the ordinary turning movement exerted by the hand of the user.

In Figures 3 and 4 there is depicted an alternative arrangement in which instead of providing an entirely separate and completely detachable handle member in the form of a tommy bar, the handle member which is again depicted at 27 is hingedly connected to the upper end of the tubular portion 16 which is made of a greater axial length than is the case with the preceding construction, the cylindrical part 14 of the preceding construction being omitted so that the striking head element 12 is mounted directly upon such upper end of the tubular portion 16.

In this arrangement the handle member 27 is of part circular form in cross section as shown in Figure 4 so that its inner face 28 corresponds to the shape of the cylindrical exterior of the tubular portion 16 and the handle member 27 is provided at one end with a pair of ears 29 disposed on opposite sides of the upper end of the tubular portion 16, which ears are pivotally connected to trunnions 30 which project diametrically on opposite sides of the upper end of the tubular portion 16, the arrangement being such that the handle member can be pivoted relative to the tubular portion to an operative position in which it extends substantially perpendicular to the axis of rotation of the tool as shown in dotted outline in Figure 3 to an inoperative position in which it extends parallel to such axis in engagement with the exterior of the tubular portion 16 as shown in the drawing.

The handle member is prevented from moving beyond the operative position indicated, by the abutment of the part 31 thereon against the adjacent side 32 of the tubular portion.

The outer end of the handle member is provided with a pair of ears 33 the outer end edges 34 of which are each adapted when the handle is in the inoperative position illustrated to engage with the ends of the pin 18 which in this construction as shown in Figure 4 project beyond the adjacent periphery of the tubular portion 16 so that when the handle is in the inoperative position and the tool is used as a screwdriver in the ordinary way as already described, the engagement between the ears 33 on the handle and the opposite ends of the pin 18 retain the latter at the end of the two slots 17 in the position illustrated so that all relative turning movement between the tubular portion 16 and the screwdriver bit 11 is prevented and a positive torque is applied at all times under these conditions from the tubular portion 16 to the screwdriver bit 11.

With either of the above described constructions, in practice two tools would be provided with the slots 17 inclined in one direction in one tool and in the other direction in the other tool so as in the one case to impart rotational torque to the screw driver.

A tool in accordance with the present invention is intended solely for manual operation and is particularly convenient for that purpose in that one hand of the operator when grasping the handle member 27 can readily hold the striking head element against rotation, leaving the other hand of the operator perfectly free to wield the hammer or other percussion tool.

With either of the constructions illustrated the operating element 10 may be adapted for engagement with other forms of threaded members and may, for example, have its bit 11 replaced by a spanner or wrench part for engaging with a nut or bolt head. Further if desired with either illustrated construction, the tubular portion 16 may be rigidly connected to the operating element 10 and the pin 18 may be rigidly connected to the striking head element 12.

With either of the constructions illustrated, the operating element may be adapted for use for engagement with threaded members other than conventional slotted screws.

What I claim then is:

1. A manually operable tool for the purpose described comprising a tubular body open at one end, a tool carrying element slideable within the open end of said body axially thereof and adapted operably to engage with the work, said body having closed ended slots in opposite sides of its tubular wall, said slots being oppositely inclined to an equal extent to the longitudinal axis of said tubular body, projections on the opposite sides of said tool carrying element working one within each slot and extending therethrough beyond the periphery of the adjacent part of the tubular body, an abutment rigid with said body within the interior thereof spaced axially of said tool carrying element, a compression spring acting between said abutment and said tool carrying element adapted to displace the latter towards the open end of said body to the extent permitted by the engagement between the projections and the slot ends, said tubular body having a striking head on the end thereof remote from the tool carrying element, a handle hinged to said tubular body about an axis transverse to the body axis at a position adjacent the striking head and adapted to pivot relative to the body between an operative position in which it extends substantially at right angles to the body axis to an inoperative position in which it extends along the length of the tubular body adjacent its exterior, and said handle in its inoperative position engaging said projections and retaining them against movement in a direction along the length of the slots.

2. A manually operable tool for the purpose described comprising a tubular body open at one end, a tool carrying element slideable within the open end of said body axially thereof and adapted operably to engage with the work, said body having closed ended slots in opposite sides of its tubular wall, said slots being oppositely inclined and to an equal extent to the longitudinal axis of said tubular body, projections on the opposite sides of said tool carrying element working one within each slot and extending therethrough beyond the periphery of the adjacent part of the tubular body, an abutment rigid with said body

within the interior thereof spaced axially of said tool carrying element, a compression spring acting between said abutment and said tool carrying element adapted to displace the latter towards the open end of said body to the extent permitted by the engagement between the projections and the slot ends, said tubular body having a striking head on the end thereof remote from the tool carrying element, a handle hinged to said tubular body about an axis transverse to the body axis at 10 a position adjacent the striking head and adapted to pivot relative to the body between an operative position in which it extends substantially at right angles to the body axis to an inoperative position in which it extends along the length of the tubular body adjacent its exterior, and said handle in its inoperative position engaging said projections on the side thereof opposite to the ends of the slots which are nearest to the tool carrying element and in such position retaining the projections in engagement with such slot ends, for the purpose specified.

3. A tool according to claim 2 wherein the

5 tubular body is of cylindrical form externally, the handle being of part circular form in cross section so as in its inoperative position to embrace the exterior of the body and being provided at its free end with ears each engaging with one of said two projections.

JOHN CHARLES SHARMAN.
